UNITED STATES PATENT OFFICE.

HERBERT O. RUSSELL, OF DETROIT, MICHIGAN, AND CHARLES LEIGH PAULUS, OF DAYTON, OHIO.

FLEXIBLE-SHAFT SYNCHRONIZING GEAR.

Application filed April 18, 1922. Serial No. 555,399.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Flexible-Shaft Synchronizing Gears, of which the following is a specification.

This invention relates to synchronizing gear for machine guns whereby the bullets from a machine gun are caused to pass between the blades of an aircraft propeller without striking them. The object of the invention is to produce a synchronizing gear of extremely light and simple construction, reliable in operation, containing a minimum number of parts and capable of more universal installation than any other known means at present in use, for the purpose of synchronizing an aircraft machine gun with the blades of the propeller.

With the above and other objects in view, the invention consists of the novel construction, combination and arrangement herein fully described, illustrated and claimed.

In the accompanying drawings:

Figure 1 is a sectional view of the synchronizing gear.

Figure 2 is a section taken at a right angle to Figure 1.

The synchronizing gear contemplated in this invention is driven by a flexible driving shaft 1 in turn driven by the engine either at propeller speed or at some suitable direct ratio of the propeller speed, said flexible shaft running to the housing 2 of a trigger motor attached to the side of the machine gun.

The flexible shaft 1 splines or its otherwise connected to the driving shaft 3 of the trigger motor which shaft is mounted in ball bearings in the housing of the trigger motor as shown in Figure 1. Attached to the shaft 3 by means of opposing serrated discs 4 and 4' and a clamping bolt 5 is a cam 6. The cam 6 operates against the sear slide operating plunger 7 which in turn operates the sear slide of the gun. At every rotation of the shaft 3, the humps upon the cam 6 work against the plunger 7 and push the latter outwardly, downwardly as shown in Fig. 1, to gun firing position,

in case the bolt of the machine gun is in 55 the proper position.

The function of the serrated discs is to permit adjustment of the position of the humps of the cam with reference to the shaft in order to time the firing of the 60 machine gun properly with reference to the position of the propeller blades.

The operation of the plunger 7 which fires the machine gun is controlled by a Bowden wire control 7' connected to a control plunger 8 working through the side of the trigger motor as shown in Figure 2. When the control plunger 8 is in its forward position as is shown in Figure 1 it forces the sear slide operating plunger 70 downwardly and prevents it from coming in contact with the cam 6 and thus being operated. The mechanism of the plunger 7 is similar to that of the slide in the Nelson gun control trigger motor for the 75 Browning gun. Upon the control plunger being withdrawn from contact with the sear slide operating plunger, the latter is moved inwardly toward the cam, upwardly as shown in Figure 1 by a spring 9 until it is in 80 operative relation to the cam 6 and thereafter the sear slide operating plunger is again operated by the cam, firing the mechanism. When the sear slide operating plunger is in the outward position, or downward, as shown in Figure 1, the machine gun bolt comes home after the last shot is fired, and the sear slide 10 of the machine gun strikes against the side of the sear slide operating plunger 7 at 11, slightly 85 displacing it into a recess 12 and rotating it out of the normal path of the sear slide of the gun, so that thereafter it is impossible for the gun to be fired until the control plunger 8 is withdrawn and the sear 90 slide operating plunger 7 moved back to its operative position by the spring 9. When the sear slide operating plunger 7 is thus again straightened out, the end thereof will effect the firing of the gun. 100

It will be noted that the sear slide operating plunger 7 is shown in the down position with its lower end protruding through the side plate of the gun. This plunger is held in this position by the control plunger 8, 105 at all times when the gun is not firing. This is made possible by the clearance cut 12 because of the fact that as the bolt goes

to the rear, the cocking lever cocks the firing pin 13 allowing the sear slide 10 to slide over into place. As the bolt returns to the forward position, the sear slide strikes the sear slide operating plunger 7 at a point indicated at 11. This forces the sear slide operating plunger forward into the clearance 10, in which position it stands until the control plunger 8 is removed from above the sear slide operating plunger 7 allowing the spring 9 to force the plunger up into contact with the trigger motor cam 6. The trigger motor spring 9 is located in such a position as to force the lower end of the sear slide operating plunger over into alignment with the gun sear slide as it moves upward. The trigger motor cam 6 having two lobes and being in constant rotation driven by a flexible shaft from the engine, causes two cycles of the trigger motor plunger per revolution of the propeller.

The cycle of function described is known as the single shot feature of this invention, inasmuch as it causes the gun to be fired at the same position in the rotation of the cam in every cycle of its movement. This is due to the fact that should the bolt be returning to its forward position and the sear slide operating plunger be on its downward stroke at the same instant, the sharp edge at the rear of the sear slide operating plunger or will not ride the top face of the sear slide. Should the sear slide be slightly in advance of the movement of the plunger, the plunger will depress the slide and fire the gun at exactly the same instant as it would fire in any other cycle. But should the plunger be slightly in advance of the sear slide of the gun, it will be tilted forward and fail to fire the gun. The next cycle of the cam would allow the plunger to rise. The trigger motor spring E would align the plunger and the sear slide of the gun and fire the gun at the next cycle of the cam F.

Another distinctive feature of the synchronizing gear above described resides in the fact that the flexible shaft 1 operates continuously and that firing is started and stopped by moving the slide 7 into and out of operative contact with the cam 6. Heretofore the firing operation has been controlled by starting and stopping the flexible shaft which operates the trigger motor, requiring a much stronger and heavier shaft and a more complicated mechanism to insure the instantaneous starting and stopping of the machine gun.

Having thus described our invention, we claim:

1. In a synchronizing gear for machine guns, an engine driven shaft terminating at one end in a serrated disc, a cam shaft terminating at one end in a serrated disc adapted to mesh with said first named disc to effect the adjustment of said cam shaft in

relation to said first named shaft about their longitudinal axes, a sear slide operating plunger adapted to be actuated by the cams on said cam shaft.

2. In synchronizing gear for machine guns, an engine driven shaft, a sear-operating slide, a cam for actuating said slide carried by said shaft, and means for retarding or advancing the lead of same by adjusting said cam around the longitudinal axis of the shaft, said means comprising serrated contacting faces on abutting sections of the shaft, and clamping means to hold said faces against relative movement.

3. In synchronizing gear for machine guns, a trigger motor embodying a housing, a driven shaft, a cam on said shaft, and a sear slide operating plunger adapted to be actuated by said cam, and a control means for moving said sear slide operating plunger into and out of operative position.

4. In synchronizing gear for machine guns, a trigger motor embodying a housing, a driven shaft, a cam on said shaft and a sear slide operating plunger adapted to be actuated by said cam, and a manual control means for moving said sear slide operating plunger into and out of operative position.

5. In a synchronizing gear for machine guns, a trigger motor embodying a housing, a driving shaft, a cam on said shaft, a sear slide operating plunger adapted to be actuated by said cam, control means for said sear slide operating plunger embodying means for depressing the same to a position where it will be out of contact with said cam.

6. In a synchronizing gear for machine guns, a trigger motor embodying a housing, a driving shaft, a cam on said shaft, a sear slide operating plunger adapted to be actuated by said cam, control means for said sear slide operating plunger embodying means for depressing the same into the path of the sear slide of the gun with which it is to be used.

7. In a synchronizing gear for machine guns, a trigger motor embodying a housing, a driving shaft, a cam on said shaft, a sear slide operating plunger adapted to be actuated by said cam, control means for said sear slide operating plunger embodying means for depressing the same to a position where it will be out of contact with said cam and into the path of the sear slide of the gun in connection with which it is to be used.

8. In synchronizing gear for machine guns, a trigger motor embodying a housing, a driving shaft, a cam on said shaft, and a sear-operating slide adapted to be moved out of operative position when struck by the sear slide of the gun.

9. In synchronizing gear for machine guns, a trigger motor embodying a housing, a driving shaft, a cam on said shaft, and a

sear-operating slide adapted to be moved out of operative position when struck by the sear slide of the gun, said sear-operating slide being partially rotatable.

5 10. In synchronizing gear for machine guns, a trigger motor embodying a housing, a driving shaft, a cam on said shaft, and a sear-operating slide adapted to be moved

out of operative position when struck by the sear slide of the gun, and manually-controlled means for holding said sear-operating slide in a projected position. 10

In testimony whereof we affix our signatures.

HERBERT O. RUSSELL.

CHARLES LEIGH PAULUS.
